United States Patent Office

Des. 203,616
Patented Feb. 1, 1966

203,616

SPATULA OR SIMILAR ARTICLE

James L. Hvale, Chicago, Ill., assignor to Flambeau Plastics Corporation, a corporation of Wisconsin

Filed Apr. 2, 1965, Ser. No. 84,572

Term of patent 14 years

(Cl. D44—29)

I claim:

The ornamental design for a spatula or similar article, substantially as shown.
